(57) **CLAIM**

The ornamental design for a desktop monitor stand, as shown and described.

DESCRIPTION

FIG. 1 is a front right perspective view of a desktop monitor stand showing my new design;

FIG. 2 is a front left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a front right perspective view of a desktop monitor stand showing an alternative embodiment of my new design;

FIG. 9 is a front left perspective view thereof;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a front right perspective view of a desktop monitor stand showing another alternative embodiment of my new design;

FIG. 16 is a front left perspective view thereof;

FIG. 17 is a front view thereof;

FIG. 18 is a rear view thereof;

FIG. 19 is a right side view thereof;

FIG. 20 is a left side view thereof;

FIG. 21 is a top view thereof;

FIG. 22 is a front right perspective view of a Desktop Monitor Stand showing another alternative embodiment of my new design;

FIG. 23 is a front left perspective view thereof;

FIG. 24 is a front view thereof;

FIG. 25 is a rear view thereof;

FIG. 26 is a right side view thereof;

FIG. 27 is a left side view thereof; and,

FIG. 28 is a top view thereof.

The broken lines immediately adjacent to the shaded area define the bounds of the claimed design and form no part thereof. The broken lines depicting the remainder of the desktop monitor stand form no part of the claimed design.

1 Claim, 28 Drawing Sheets
